Primary Examiner — Prabhakar G Deshmukh

(57) **CLAIM**

What is claimed is the ornamental design for a joystick ring, as shown and described.

DESCRIPTION

FIG. 1 is a top, front, left-side perspective view of a joystick ring;

FIG. 2 is top view thereof;

FIG. 3 is a front view thereof;

FIG. 4 is a right-side view thereof;

FIG. 5 is a left-side view thereof;

FIG. 6 is a rear view thereof;

FIG. 7 is a bottom view thereof; and,

FIG. 8 is a bottom, front, right-side perspective view thereof.

(Continued)

The broken lines shown in the drawings are for illustrative purposes only and form no part of the claimed design.
